UNITED STATES PATENT OFFICE

154,109

DESIGN FOR A FISHING LURE

George B. Espey and Gilbert D. Waite,
Cleveland, Ohio

Application June 2, 1947, Serial No. 139,408

Term of patent 14 years

(Cl. D31—4)

To all whom it may concern:

Be it known that we, George B. Espey and Gilbert D. Waite, both citizens of the United States, and residing at Cleveland, in the county of Cuyahoga and State of Ohio, have invented a new, original, and ornamental Design for a Fishing Lure, of which the following is a specification, reference being had to the accompanying drawing, forming a part thereof.

Figure 1 is a top view of a fishing lure, showing our new design;

Figure 2 is a side view thereof; and

Figures 3, 4, 5, 6 and 7 are transverse sectional views taken, respectively, at lines 3—3, 4—4, 5—5, 6—6 and 7—7 of Figure 1.

We claim:

The ornamental design for a fishing lure, substantially as shown.

GEORGE B. ESPEY.
GILBERT D. WAITE.
